CARD FILING DEVICE

Herbert Vaughan Davies, London, England, assignor to
Manifoldia Limited, West Bromwich, England, a British
company

Application July 3, 1952, Serial No. 297,147

Claims priority, application Great Britain July 13, 1951

2 Claims. (Cl. 129—16)

This invention relates to card filing devices of the rotary drum type in which cards are mounted upon a rotatable drum in radially extending relationship, the drum being rotatable about a horizontal axis so that the cards can be traversed in succession past a viewing station at the top of the drum.

It is an object of the invention to provide an improved device of the above kind in which separation of the individual cards at the viewing station is facilitated.

The invention provides a card filing device of this type characterized by the provision of a pair of card-holding elements mounted upon the drum for movement therewith, each card-holding element comprising an elongated element, which is extensible in the longitudinal direction and which is mounted upon the drum in the form of an annular ring, said card-holding elements being spaced apart axially of the drum and each having a plurality of card-receiving portions each of which receives an edge of a card when cards are arranged in radially extending fashion on the drum.

The cards have a component of upward movement to the viewing station and a component of downward movement away therefrom so that the weight of the cards approaching and leaving the viewing station tends to extend the elements as aforesaid.

Each element is preferably a zig-zag of folded strip form, the edges of the cards being received within the folds at the inner side of the element. At the outer side each element may make interlocking engagement with a guide rail on the drum, the engagement holding the element to the rail while permitting sliding movement of the folds along the rail. For example each zig-zag limb of the element may be formed with a slot of T or like shape providing an elongated bar and a stem in a direction transverse thereto, the length of the bar being transverse to the length of the element and the stem extending to the rear face of the element and there may be a guide rail received within the bar of the slot, the stem permitting passage of the folds of the element past supporting means for the rail during sliding movement of the folds along the rail.

Each element may be built up of short sections and when it is of zig-zag form each section may provide one fold for the reception of one card and the arrangement may permit of the insertion of one or more additional sections between pairs of adjacent sections.

When the elements are supported on guide rails as above described the cards may have notches in their edges fitting over the rails to hold the cards in place.

Some specific examples of card filing devices embodying the above and other features of the invention will now be described with reference to the drawings in which:

Figure 1 is a perspective view of a card filing device embodying a carrier in the form of a drum,

Figure 2 is a vertical section through the device shown in Figure 1,

2

Figure 3 is a section on the line III—III in Figure 2, through the drum,

Figure 4 is a detail perspective view,

Figure 5 is a view showing one section of the extensible element,

Figure 6 is a view of a card,

Figure 7 is a view of a separator card,

Figure 8 is a view corresponding to a portion of Figure 3 on an enlarged scale of a modification,

Figure 9 is a view of one of the cards employed in the modification shown in Figure 8.

In the construction shown in Figures 1—7 the carrier is in the form of a drum 1 supported in a casing 2 for rotation about a horizontal axis. A handwheel 3 outside the casing and secured to the drum spindle 4 is provided for effecting rotation of the drum. An annular rail 5 of rectangular cross-section is secured to the inner face of each side of the drum. The rails are concentric with the drum and have their greater cross-sectional dimension extending radially, the rails being quite thin in the axial direction. The rails are held spaced away from the inner face of the drum by securing means 6 positioned at the centre of the radial width of the rails.

Attached to each rail 5 there is an extensible zig-zag card holding element 10. Each element is of annular form. The element is made up of sections 11 (Figures 4 and 5) each consisting of one pair of reverse folds (i. e., have the form of the letter N), and each folded from paper, card flexible sheet plastic or the like. The sections are assembled with one free limb received within the fold of the adjacent section as may be seen from Figure 4, thereby to form a continuous ring when secured to the rail as later described. At the back of each limb of each section there is cut a T-shaped slot 12 so as to

form, in the assembly, a T-shaped slot extending around the whole of the ring. The slot extends inwardly to about half the depth of the zig-zag. The ring is held to the rail 5 by fitting the slot over the rail so that the rail is received within the cross-bar of the slot. This may be done by temporarily removing a section of the rail or by bending the tongues 13 at the back of the ring. Initially the sections are first assembled as above described into the form of a pack which is fitted as such onto the rail and then opened out to extend around the rail. If it is then desired to insert one or more additional sections at any position in the ring this may be effected by first removing the portion of the ring at that position from the rail, separating the sections at that position, inserting the new section or sections and then replacing the ring on the rail.

The T-shaped slot holds the extensible ring on the rail but permits the folds to slide along it and to pass the supports 6.

In use the cards 15 are received within the folds of the two elements 10, there being normally only one card in each pair of folds although more may be inserted if desired, and as the drum is rotated the weight of the cards approaching the viewing station 16 at the top of the drum is opposed to the weight of the cards leaving the viewing station and consequently the folds in the portions of the zig-zag elements passing the viewing station tend to open out and separate the cards so that inspection or selection is facilitated. At the lower parts of the drum the cards close up to one another as indicated in Figure 3.

The cards are provided with notches 18 in their side edges which fit over the rails 5 to hold the cards in position.

To assist in the gravitational operation of the device some of the cards at intervals around the drum may em-

body weights as indicated at 20 in Figure 7 or the cards may be of heavier material (e. g., metal). Such weighted or heavier cards may, for example, be used to divide the cards into sections, for instance in the case of alphabetically arranged cards there may be a weighted card between the cards of each letter.

Figures 8 and 9 show a modification of the above example in which the cards 25 are folded to form pockets within which loose sheets 26 may be placed. It is found that when the folds are closed up at the bottom of the drum by the weight of the cards they have sufficient grip to prevent the loose sheets falling out. The two limbs of the folded cards are received within adjacent folds of the zig-zag elements (see Figure 8) to ensure that the pockets will open out at the viewing station. The folds in the cards may be reinforced as shown at 27.

It is not essential that, in use, only one card be received within a fold. If desired there may be two or more cards in one fold, the cards being, for example, related in some way such as continuations of one another.

I claim:

1. A card filing device comprising a drum rotatable about a horizontal axis, said drum comprising a spindle and a pair of side plates mounted thereon in axially spaced relationship, an annular rail mounted upon the inner face of each side plate, a pair of card-holding elements, one mounted upon each said rail for movement therewith, each card-holding element comprising an elongated element, of zig-zag folded strip form which is extensible

in the longitudinal direction, each of the folds at the outer side of each element being provided with cut-out slots of T-shape which engage over the adjacent annular rail and the edges of the cards being received within the folds at the inner sides of the elements when cards are arranged in radially extending fashion on the drum.

2. A card filing device according to claim 1 in which each element is built up of short sections which are detachably engaged one with another.
